UNITED STATES PATENT OFFICE.

RALPH E. BARKER, OF LYNN, MASSACHUSETTS, ASSIGNOR TO GENERAL ELECTRIC COMPANY, A CORPORATION OF NEW YORK.

CONTROLLING DEVICE FOR ELECTRIC MOTORS.

No. 895,836.

Specification of Letters Patent.

Patented Aug. 11, 1908.

Application filed December 26, 1907. Serial No. 408,177.

To all whom it may concern:

Be it known that I, RALPH E. BARKER, a citizen of the United States, residing at Lynn, county of Essex, State of Massachusetts, have invented certain new and useful Improvements in Controlling Devices for Electric Motors, of which the following is a specification.

This invention relates to devices for controlling electric motor circuits and has for its object the provision of a device of this character in which certain automatic features of operation are combined with extreme simplicity of construction in such a manner as 15 to produce a thoroughly reliable and efficient arrangement.

My invention relates more specifically to devices for controlling alternating current motors, and particularly those of the single 20 phase induction type. It is well known that this type of motor will not start from rest unless provided with special starting means, such as auxiliary starting windings or phase-splitting devices or both. It is generally 25 desirable when such starting devices are employed that they be cut out of circuit when the motor reaches running speed, since they are ordinarily intended to be in circuit for a short time only and would otherwise 30 become overheated. Furthermore, the running efficiency of the motor would be impaired by keeping the starting devices in circuit.

One of the objects of my invention is to 35 provide a simple starting device for this type of motor in which the starting winding is first connected in the motor circuit and then automatically cut out after a predetermined interval.

40 In carrying out my invention, I provide in connection with a manually-operated switch, which closes the circuit of the main motor winding, an auxiliary circuit controlling mechanism in connection with said 45 switch which closes the circuit of the starting winding when the switch is closed, and at the same time, so arranges the parts that the auxiliary circuit controller will operate automatically to cut out the starting winding.

50 In the accompanying drawing, in which I have shown my invention embodied in concrete form, Figure 1 is a side elevation of a starting device embodying my invention; Fig. 2 is a plan view thereof showing

the circuit connections; and Fig. 3 is a sectional elevation of the same.

Referring to the drawings, 10 is an insulating base of slate, soapstone or the like, having mounted thereon a switch arm pivoted upon a stud 11. This switch arm consists of an operating handle 12, insulated from the conducting pivot 11, and a switch-blade 13 moved by said handle, but electrically connected with the stud. Secured to the switch and movable therewith is an elongated 65 bracket 14 arranged to receive a metallic ball 15, which moves longitudinally of the bracket. This bracket consists of elongated metallic strips 16 and 17, the former being electrically connected with the switch-blade 13, 70 while the latter is insulated therefrom. These strips are mounted in the bracket parallel with each other and their adjacent faces are grooved at 18 so as to receive the ball between them. The ball is adapted to travel 75 back and forth by gravity along the conducting strips and rest at opposite ends thereof against the insulating portion 19, which holds the ball in place, and assures a short interval of time for the starting of the motor. 80 The switch-blade 13 is adapted to enter the conducting clip 20 which is made adjustable, as shown.

The arrangement of circuits and the mode of operation are as follows: Normally, the 85 switch mechanism stands in the position shown in full lines in Fig. 2. To start the motor, the switch is moved to the position shown in dotted lines. When the switch-blade 13 enters the clip 20, the circuit through 90 the main motor winding M is completed. At the same time, the ball 15 starts towards the opposite end of the bracket as the latter is moved towards horizontal position. By the time the blade reaches the clip, the ball has 95 bridged the contacting surfaces 16 and 17 so that a circuit is completed through the starting winding S of the motor from the positive main to the starting winding, conductor 21, 100 conducting strip 17, ball 15, strip 16, switch blade 13 and back to the negative main. The starting winding and the main winding are thus connected in parallel circuit, so that the motor is started. As the switch is closed, the bracket is moved away from the horizontal position, and the ball moves to the opposite end of the bracket. During the movement of the ball, the starting winding is in

circuit, but when the ball reaches the opposite end of the bracket, the starting winding is cut out, leaving the main winding alone in circuit. I have shown my device as arranged 5 for starting single-phase motors with the type of starting connection known as the "mono-cyclic" connection, but the particular starting connections shown and described form no part of my invention.

10 While my starting device is intended ordinarily for use in connection with very small motors, as for instance, those used in connection with phonographs, it should be understood that I do not limit my invention to 15 this particular application, since the principle herein involved may be employed in controlling devices for various types and sizes of motors. I do not, therefore, regard my invention as being limited to the above structural arrangement, circuit connections or application, except in so far as it is limited by the scope of the claims annexed hereto.

What I claim as new and desire to secure by Letters Patent of the United States, is,— 25 1. The combination with an electric motor having different connections of the windings for starting and running, of a switch for closing the circuit through said windings, and means in connection with said switch 30 and operating independently thereof for automatically changing said windings.

2. The combination with an electric motor having different connections of the windings for starting and running, of a switch for 35 closing the circuit through said windings, and an element movable independently of said switch arm and set in motion thereby for changing said windings.

3. The combination with an electric motor 40 having different connections of the windings for starting and running, of a manually operated switch for closing the circuit through said windings, and an element set in motion by the closing of said switch and movable 45 independently thereof for automatically changing said windings after a predetermined interval.

4. The combination with an electric motor 50 having different connections of the windings for starting and running, of a manually operated switch for closing the circuit through said windings, relatively movable contacting surfaces associated with said switch for controlling said windings, said surfaces being 55 arranged to move by gravity to affect the windings when said switch is operated.

5. The combination with an electric motor 60 having different connections of windings for

starting and running, of a manually operated switch for closing the circuit through said 60 windings, a contacting surface for controlling the circuit of said windings movable with said switch, and an element movable upon said contact to change said windings when the contact is moved away from the horizontal 65 position.

6. The combination with an electric motor 70 having different connections of windings for starting and running, of a manually-operated switch for closing the circuit through said 75 windings, an elongated contacting surface movable towards and from a horizontal position by the operation of said switch, and an element movable by gravity over said surface for changing said windings.

7. The combination with an electric motor 80 having different connections of windings for starting and running, of a manually-operated switch for closing the circuit through said windings, an elongated and grooved contacting surface movable towards and from a horizontal position by the operation of said switch, and a ball movable by gravity over 85 said surface for changing the connections of said windings.

8. A starting device for electric motors comprising a switch for closing the motor circuit, a contacting surface movable towards and from a horizontal position by the operation of said switch, and an element movable by gravity over 90 said surface to affect the circuit.

9. A starting device for electric motors, comprising a manually-operated switch for closing the motor circuit, an elongated contacting surface movable therewith having a horizontal position between the full open and full closed positions of said switch, and an element movable by gravity over 95 said surface to affect the circuit.

10. A starting device for electric motors comprising a manually-operated switch for closing the motor circuit, a grooved contacting surface movable therewith having a horizontal position between full open and full 100 closed positions of said switch, and a ball movable by gravity in said groove to affect the circuit.

In witness whereof, I have hereunto set my hand this twenty-third day of December, 110 1907.

RALPH E. BARKER.
